(57) **CLAIM**

The ornamental design for a handle for an orthopedic extraction tool, as shown and described.

DESCRIPTION

FIG. 1 is a perspective view of a handle for an orthopedic extraction tool in accordance with the new design;

FIG. 2 is a front view of the handle for an orthopedic extraction tool of FIG. 1;

FIG. 3 is a rear view of the handle for an orthopedic extraction tool of FIG. 1;

FIG. 4 is a left side view of the handle for an orthopedic extraction tool of FIG. 1;

FIG. 5 is a right side view of the handle for an orthopedic extraction tool of FIG. 1;

FIG. 6 is a top view of the handle for an orthopedic extraction tool of FIG. 1; and,

FIG. 7 is a bottom view of the handle for an orthopedic extraction tool of FIG. 1.

In the drawings, the broken lines illustrate portions of the handle for an orthopedic extraction tool that form no part of the claimed design.
